(57) CLAIM

The ornamental design for a tiered serving tray with removable condiment serving racks, as shown and described.

DESCRIPTION

FIG. 1 is a front perspective view of a tiered serving tray with removable condiment serving racks showing my new design;

FIG. 2 is another front perspective view thereof with the warming drawer pulled out;

FIG. 3 is another front perspective view thereof, with the condiment serving racks removed for clarity of surface detail;

FIG. 4 is a bottom perspective view thereof;

FIG. 5 is a top plan view of the article as shown from FIG. 1;

FIG. 6 is a bottom plan view thereof;

FIG. 7 is a side view thereof;

FIG. 8 is another side view thereof;

FIG. 9 is a front view thereof; and,

FIG. 10 is a back view of thereof.

The broken lines are shown for the purpose of illustrating parts of the article that form no part of the claim.

1 Claim, 7 Drawing Sheets
